**RAILROAD GRADE CROSSING PROTECTION
 SYSTEM**

Carroll M. Steele, Los Altos, and Arlo C. Krout, San Carlos, Calif., assignors to Southern Pacific Company, San Francisco, Calif., a corporation of Delaware
 Filed Sept. 30, 1963, Ser. No. 314,578
 17 Claims. (Cl. 246—128)

This invention relates to systems for providing a warning at a railroad grade crossing when a train is approaching and, more particularly, to improvements therein. This application is a continuation-in-part of our application Serial No. 19,747, filed April 4, 1960 and entitled Railroad Grade-Crossing Protection System. Presently employed grade-crossing warning systems, although reliable, are fairly costly to install and maintain.

An object of this invention is to provide a novel railroad grade-crossing warning system whereby the delay to cross traffic is minimized.

Yet another object of the present invention is the provision of a unique railroad grade-crossing warning system which is easy to install and maintain.

Still another object of the present invention is the provision of a novel railroad grade-crossing warning system which is reliable.

These and other objects of the present invention are achieved in an arrangement wherein the railroad track is considered as a shorted transmission line in which the short is provided by the train. An alternating current signal with a substantially constant current level is applied to the tracks at the location of the grade crossing. The voltage existing across the tracks as the train, and therefore the short, approaches the grade crossing will diminish. Thus the amplitude of this voltage provides a measure of the distance of the train from the track while the rate at which this voltage diminishes provides a measure of the velocity of the train. With these parameters, it becomes possible to estimate the time of the train's arrival at the crossing. Knowing the time of arrival, the system can start warning signals at such a time as will provide the least possible delay for cross traffic. The signal representative of distance and the derived signal therefrom representative of velocity are combined to provide a third voltage representative of the time required for the train to arrive at the railroad grade crossing.

The novel features that are considered characteristic of this invention are set forth with particularity in the appended claims. The invention itself, both as to its organization and method of operation, as well as additional objects and advantages thereof, will best be understood from the following description when read in connection with the accompanying drawings, in which:

FIGURE 1 is a block diagram of an embodiment of the invention.

FIGURE 2 is a block diagram of another embodiment of the invention.

FIGURE 3 is a block diagram of yet another embodiment of the invention.

FIGURE 4 is a block diagram showing how the embodiment of the invention is connected to several successive track sections.

FIGURES 5A, 5B are detailed block diagrams of the arrangement of FIGURE 4.

FIGURE 6 is a block diagram of a modification of the embodiment shown in FIGURE 3.

FIGURE 7 is a detailed block diagram of a portion of FIGURE 6; and

FIGURE 8 shows the waveforms of various signals present in FIGURES 6 and 7.

Reference will now be made to FIGURE 1 of the drawing which is a block diagram of one embodiment of this invention. From FIGURE 1 it will be seen that a train has a motion in the direction represented on a pair of track rails 12A, 12B. The train is at some distance L from an origin point P, P', which represents the location of a grade crossing, for example. The train motion occurs from left to right. The velocity V and acceleration A factors are therefore represented as going from left to right on the drawing. Now

$$L = \int \int (a_0 dt) dt \quad (1)$$

and integrating,

$$L = \int (a_0 t + C_0) dt \quad (2)$$

C_0 is the integration constant.

The first integral of acceleration is velocity; therefore,

$$V = a_0 t + C_0 \quad (3)$$

At $t = T_0 = 0$, $V = V_0$. Also

$$C_0 = V_0 \quad (4)$$

and

$$V = a_0 t + V_0 \quad (5)$$

Substituting, we find that

$$L = \int (a_0 t + V_0) dt \quad (6)$$

The second integral of acceleration is displacement. Therefore

$$L = \frac{a_0 t^2}{2} + V_0 t + C_0 \quad (7)$$

Now at $t = T_0 = 0$, we will let the displacement = 0. Hence

$$L = \frac{a_0 t^2}{2} + V_0 t \quad (8)$$

If we put limits on time in the above equation, we will arrive at the distance an object will travel in the time interval defined by these limits, as follows:

$$L \Big|_{T_0, T_1} = \left[\frac{a_0 t^2}{2} + V_0 t \right]_{T_0}^{T_1} = \frac{a_0 (T_1^2 - T_0^2)}{2} + V_0 (T_1 - T_0) \quad (9)$$

Since $T_0 = 0$, the above reduces to,

$$L \Big|_{T_0, T_1} = \frac{a_0 T^2}{2} + V_0 T \quad (10)$$

where T_1 is replaced by the general term T. Therefore, if a train has the distance L to go until it arrives at the crossing, it will take time T to get there. This is the basic equation of the prediction computer. In practice, L, a_0 , and V_0 are functions of time, and the computer output is a running prediction of the time required for the train to get to the crossing. Because L, a_0 , and V_0 are varying with time, the prediction equation is written as

$$L = \frac{a_0 T^2}{2} + V_0 T \quad (11)$$

$$aT^2 + 2VT - 2L = 0 \quad (12)$$

A computer in accordance with this invention will include an oscillator 14 which oscillates at a suitable frequency. It has been found that from the standpoint of obtaining best results an oscillator which provides an output having a frequency on the order of 50 cycles per second enables an optimum of results to be obtained. Higher frequencies give a higher input impedance, which is desirable, but bad track ballast conditions load the transmission line, which the rails represent, to such an extent as to make a distance measurement with the required accuracy impossible. Frequencies below 50 cycles per sec-

ond makes the loading effect less severe, but they reduce the input impedance, thus making the circuit constants and voltages more difficult to handle. The output of the oscillator is applied to excite a power amplifier 16. A resistor 18 connects one side of the power amplifier to one rail at a point P'. The other side of the power amplifier is connected to the other rail at P. The power amplifier 16 together with resistor 18 comprises a constant current generator. This delivers an input to the track at substantially a constant current.

It should be appreciated that as the train 10 approaches the points P, P' on the tracks to which current from the constant current generator is applied, the impedance of the tracks looking toward the train from those points is continuously being diminished. This follows by reason of the fact that the train comprises a short across the tracks which is moved toward the points P, P'. With current being maintained constant, the voltage at the points P, P' will continuously decrease to a minimum when the train reaches the points P, P'. Therefore, by measuring the voltage across the tracks an indication is obtained of the distance of the train from the points at which the voltage is impressed. The change with respect to time of this voltage can provide velocity information, and the second derivative of this voltage information provides information as to the acceleration of the train.

Accordingly, a narrow bandpass filter centered at 50 cycles which is connected to the same points on the track as the constant current generator receives a voltage representative of length of track L or distance between the train and the points P, P'. This voltage is an alternating current one, which is modulated by the motion of the train toward the points P, P'. The output of the narrow bandpass filter is applied to a rectifier 22, which demodulates this voltage and applies its output to a low-pass filter 24. Its output is a voltage representative of the distance L.

The amplifier output is applied to a differentiator circuit 26. The output of the differentiator circuit 26 will be a voltage representative of the velocity V of the train. This voltage is applied to a second differentiator circuit 28 and also to one input of a multiplier circuit 30. The second differentiator circuit 28 differentiates its input with respect to time and provides as an output a voltage representative of the acceleration of the train. The output of the second differentiator circuit is applied to a multiplier circuit 32.

Now considering the output of the amplifier 20 again, in addition to being applied to the differentiator circuit 26, it is also applied to an inverter circuit 34. The inverter circuit merely phase inverts the input so that the output represents the negative of the input, which here is $-L$. The output of the inverter circuit 34 is applied to an amplifier 36, which multiplies its input by a factor of two. The output of this $2\times$ -amplifier 36 is applied to one input of a summing amplifier 38. The summing amplifier 38 also receives the output of the multiplier circuit 32. The multiplier circuit 30 applies its output to another $2\times$ -amplifier 40. This amplifier output is then applied as a third input to the summing amplifier 38. The output of the summing amplifier 38 is applied to a high-gain amplifier 42. The output of this high-gain amplifier is fed back as the second input to a multiplier circuit 30 and as both of the inputs of a multiplier circuit 44. The output of the multiplier circuit 44 is applied as a second input to the multiplier circuit 32.

The input to the summing amplifier 38 from the amplifier 36 is $-2L$. Assuming the inputs to multiplier circuit 30 to be the voltage-representative velocity V and another voltage which it will be assumed represents the estimated time of arrival t of the train at points P, P', then the output of the multiplier circuit is the product Vt , and the input to the summing amplifier from the $2\times$ -amplifier 40 is a quantity $2Vt$. Using the previous

assumption, then the multiplier circuit 44 provides as an output the quantity t^2 , which is multiplied by the acceleration-representative voltage; therefore, the input to the summing amplifier from multiplier circuit 32 is at^2 . The summing amplifier adds these quantities and if the voltage t has the right value, its output should be zero. The purpose of the high-gain amplifier 42 is to provide an output which is fed back in the manner shown to force the summing amplifier output toward zero. With a sufficiently high gain for the amplifier, this condition is approached. The output of the high-gain amplifier 42 therefore will be the quantity t or the expected arrival time of the train at the points P, P'. This quantity is applied to an amplitude comparator circuit 46. Thus, the voltage t is compared by this circuit with a voltage provided by a voltage source 48. The voltage provided by the voltage source 48 has an amplitude representing the time at which it is desired that the warning device at the railroad grade crossing be actuated. Thus, the amplitude comparator circuit provides an output to a warning device 50 whenever the voltage t and that of the voltage source are equal, or, if desired, when t is greater than the voltage from the source.

It is possible to predict the time of arrival of the train at a crossing without employing the second derivative or acceleration. This results in an embodiment of the invention which is simpler and therefore preferable to the one shown in FIGURE 1. Such simpler embodiment of the invention is shown in FIGURE 2. A prediction equation may be established as follows:

$$\frac{TdL}{dt} - L = 0 \quad (13)$$

where T = predicted arrival time, L = distance from the crossing to the trains, and dL/dt = the speed of the train. All that Equation 13 sets forth is the well known concept that the product of the velocity, times the time, minus the distance, equals zero.

FIGURE 2 is a block diagram of an arrangement in accordance with this invention for providing the desired prediction time and actuating a warning device when this predicted time approaches a desired value. The train 10 on rails 12A, 12B is approaching the points P, P'. These are excited by an oscillator 60 which has the desired frequency of 50 cycles per second. The oscillator output is applied to a power amplifier 62. This is connected to the points P, P' through a resistor 64. This resistor 64 together with the power amplifier 62, as before, constitutes a constant-current generator. The time-of-arrival prediction system includes a bandpass amplifier containing two active filters, respectively 66, 68. These filters are resonant to 49 and 51 cycles per second, respectively, and form a staggered tuned pair, which is four cycles at the 3-db points. The purpose of this filter is to remove noise signals from the system which do not lie close to the frequency of 50 cycles per second. The output of this bandpass amplifier is applied to a rectifier and filter circuit 70 for the purpose of removing the 50-cycles-per-second carrier component and its harmonics from the detected signal. The signal is then applied to an amplifier 72 to re-establish its level and then is applied to a cathode follower 74 for the purpose of lowering the source impedance before coupling it with the remainder of the circuits. At this point, the signal is a changing direct current voltage, proportional to the distance between the crossing points P, P' and the train. The output of the cathode follower is applied to a minimum-distance amplitude discriminator 76 which will be discussed later herein, as well as to a differentiator circuit 78. The differentiated signal which represents the velocity V is amplified and inverted by a D.C. amplifier 80. The output of the D.C. amplifier 80 is coupled to one input of a multiplier circuit 82. The output of the multiplier circuit is connected to a D.C. amplifier 84, which serves the function of amplifying

and inverting its input. The output of the D.C. amplifier 84 is applied to one input of a summing amplifier 86.

The output of the cathode follower 74 is also applied to this summing amplifier 86 as its second input. The output of the summing amplifier is applied to another D.C. amplifier 88, the output of which is applied to an amplitude discriminator 90 as well as to the multiplier circuit 82 as its second input. The amplitude discriminator 90 controls a relay amplifier 92, which operates a relay 94 connected to the warning device when the time predicted by the circuitry described equals the time set in the amplitude discriminator.

Operation of the computation feedback loop within the prediction system is as follows:

The equation for which a solution is desired is

$$L - T \left(\frac{dL}{dt} \right) = 0 \quad (14)$$

where:

L = the instantaneous distance between the train and the crossing, which is obtained at the output of cathode follower 74;

T = the instantaneous transit time required for the train to travel from its present position to the crossing, obtained at the output of D.C. amplifier 88;

dL/dt = the instantaneous speed of the train;

and the means by which it is solved are given in the following steps:

(1) A solution, T_a , is assumed, and the solution is then multiplied by the speed, dL/dt , by the multiplier circuit 82 with the following product resulting:

$$T_a \times dL/dt \quad (15)$$

(2) This product is subtracted from L in the summing amplifier 86, and the difference between the two quantities is denoted as $k(t)$, then

$$L - (T_a \times dL/dt) = k(t) \quad (16)$$

(3) $k(t)$ is greatly increased in magnitude by passing it through an amplifier 88 having a gain A . The output of this amplifier 88 is therefore

$$A[k(t)] = A[L - T_a(dL/dt)] \quad (17)$$

(4) the quantity

$$A[L - T_a(dL/dt)] \quad (18)$$

is entered into the feedback loop as the assumed solution, T_a . Therefore

$$T_a = A[L - T_a(dL/dt)] \quad (19)$$

or

$$T_a/A = L - T_a(dL/dt) \quad (20)$$

Therefore, if $A \gg T_a$,

$$O \approx L - T_a(dL/dt) \quad (21)$$

Since the only value of T_a which will satisfy this relationship is the desired solution, T , then it must be assumed that the feedback loop has forced T_a to equal T and therefore the output of the high-gain amplifier 88 is a voltage proportional to the time required for the train to proceed from its present position to the crossing.

The voltage proportional to T is coupled to an amplitude discriminator 90, where it is compared with a reference voltage supplied by a reference voltage source 91. When the reference voltage is exceeded, the discriminator 90 produces an output which is amplified and then operates the relay 94 connecting power to the warning signal.

The voltage proportional to the distance to the train also is connected to the minimum amplitude discriminator 76. This discriminator operates a relay 96 when the distance to the train is less than some preset value (i.e., 100 feet). This relay circuit acts as an override in the warning system and is used to overcome some of the prediction inaccuracies which occur when the train is moving very slowly.

Further simplification of the embodiment of the invention shown in FIGURE 2 may be achieved, if desired. Consider the block diagram of this embodiment of the invention, shown in FIGURE 3. A 50-cycle oscillator 100 drives a power amplifier 102. The output of this amplifier is applied to the rails 12A, 12B to point P directly and to point P' through a resistor 103. As before, the amplifier 102 and resistor 103 comprise a constant current generator. These points are also connected to bandpass amplifier 104 of the type described previously, which includes two active filters which are resonant at 49 and 51 cycles per second. The output of the bandpass amplifier 104 is applied to a rectifier 106. The output of the rectifier 106 is applied to a filter 108, the output from which is applied to an inverting differentiator circuit 110 and also to a summing amplifier 112. The output of the inverting differentiator circuit is applied to an amplifier 116. The output of amplifier 116 is connected to the second input of the summing amplifier 112. The summing amplifier output is connected to a high-gain amplifier 118. The output of the high-gain amplifier is applied to an amplitude comparator 120.

Voltage from a reference source 122 is also applied to the amplitude comparator to be compared with the output from the high-gain amplifier 118. The output of the amplitude comparator 120 is applied to a relay amplifier 123, which operates the warning signal relay 124 when the signal applied thereto has a sufficient amplitude. An override circuit is also provided, and this includes an amplitude discriminator 130, which receives output from the rectifier 106, and also to a relay amplifier 132 which drives a relay 134. The relay amplifier 132 receives output from the amplitude discriminator 130. The signal which is provided at the output of the filter 108 is a varying direct current voltage proportional to the distance L between the train and the excitation point. This signal is then differentiated, inverted, and amplified by the following circuitry to give a signal proportional to speed. This signal, which is added to the distance signal L by the summing amplifier, provides a result at the output of the summing amplifier which can best be expressed in an equation of the following form:

$$L - K(dL/dt) = k(t) \quad (22)$$

If it is desired to have a warning time of 30 seconds, then the gain of the amplifier following the differentiator is set to 30 and the following equation results:

$$L - 30(dL/dt) = k(t) \quad (23)$$

Consider now a train a long distance off, so that L is larger than $30 dL/dt$; under these conditions, $k(t)$ will be positive. If, however, the train proceeds at constant speed, there will be a time when L equals $30 dL/dt$ and $k(t)$ will be zero. A short time later L will be less than $30 dL/dt$ and $k(t)$ will be negative. When $k(t)$ is zero, it will be exactly thirty seconds until the train arrives at the excitation point if it does not change its speed. Therefore, all that is now required of the computer is to detect the zero-crossing point of $k(t)$. This is done by greatly amplifying $k(t)$ and using an amplitude comparator to detect the zero-crossing. The output of the comparator is coupled to a relay amplifier which operates the warning relay.

This computer differs from the previous first-order computer in that an explicit solution for the warning time T is obtained only once, and that is when the warning time is equal to that which was preset into the computer. By using this simplified predictor without the inaccurate multiplier and its associated feedback amplifiers, an increase in accuracy was obtained with no sacrifice in system performance.

In order to incorporate the computer into a warning system, it is sometimes necessary to relay information. A simplified block diagram showing transmission of information from one crossing to another is shown in FIGURE 4. The system can be described as follows: Assume

that there is a train in section No. D₂, proceeding at a velocity V toward section No. D₃. Computers C₁₂ and C₂₂ are both tracking this train; however, the train is receding from crossing X₁, and therefore this barrier has been raised. Depending upon the train speed, several conditions of the barriers ahead of the train are possible: If the speed of the train is low, barrier X₂ will lower only when the train nears the X₂ crossing. In the same situation, barrier X₃ will lower only when the train is nearing this crossing. In both cases, the computer is using only the information given to it from the track section in which the train is located. However, if the train were moving at a high speed and if the track section No. D₃ were short, it would be necessary for barrier X₃ to come down while the train is in section No. D₂. To handle this type of a situation, there is an additional circuit located in each computer to make the required computation in the following manner: To the voltage in computer C₂₂ (which represents the distance between the train and crossing X₂), there is added an additional fixed voltage proportional to the distance D₃. The resulting sum is used to compute arrival time at barrier X₃. When the train has reached a point where barrier X₃ should be lowered, a relay signal is sent via the track signal line to computer C₃₃, telling it to bring down the barrier. When the train enters section No. 10 3, computer C₃₃ will be using information derived from track section No. 3 and the relay information from C₂₂ will be dropped out. In a similar manner, computer C₃₃ can relay information to C₄₄, etc., and for trains moving in the other direction a similar situation exists.

Reference is now made to FIGURES 5A and 5B, which illustrate in more detail the simplified arrangement shown in FIGURE 4. Apparatus in FIGURE 5A providing the same function as the apparatus shown in FIGURE 3 and FIGURE 4 will have the same reference numerals applied thereto. Thus, the computers C₁₁ and C₁₂ in FIGURE 4 are shown in detail. These, in turn, have the circuit shown in FIGURE 3. Computers C₂₂ and C₂₃, as well as C₃₃ and C₃₄, which are identical with C₁₁ and C₁₂, are exemplified by the rectangular blocks.

An oscillator 100 oscillating at the preferred frequency of 50 cycles per second drives a power amplifier 102. The power amplifier excites the sections of track designated as D1 and D2 through a transformer 103. These track sections lie on either side of a crossing designated as X₁. The transformer 103 has two secondary windings 103A and 103B, which are respectively connected through resistors 105A, 105B to the track sections D1 and D2. Batteries 120A, 120B and chokes 122A, 122B are respectively connected in series with each other and then respectively across track sections D1 and D2. These batteries serve the function of providing the energy requisite for the other signaling devices (not shown) which are employed on the track. If the chokes were not used, the batteries would effectively short-circuit the tracks, as far as this invention is concerned, and thus would prevent its operation.

Aside from a common oscillator and power amplifier, the remaining structure of the two computers, corresponding to C₁₁ and C₁₂ in FIGURE 4, are identical with that shown in FIGURE 3. Therefore, these will not be redescribed here. The outputs of the high-gain summing amplifiers 112a and 112b are both applied to a common relay amplifier 123 which, when a sufficiently large signal is applied to its input, can energize the relay 124, having relay contacts 124C. When contacts 124C are closed, a grade-crossing warning device (not shown) is actuated. The outputs of the bandpass amplifiers 104A, 104B, are respectively applied to two A.C. amplifiers 136A, 136B. The output of these amplifiers is respectively applied to two rectifiers and filters 138A, 138B. The output from the rectifiers and filters is applied to two amplitude discriminators, respectively 140A, 140B. A reference voltage is respectively applied to these respective amplitude discriminators from sources

141A, 141B, which is indicated as the minimum-distance reference voltage. The purpose of this is that in the event the distance of the train is less than this minimum distance in the respective blocks D1, D2, then an output will be applied from the respective amplitude discriminators to operate the relay amplifier 123 and relay 124 to provide a warning. These circuits are used to handle the situation where the train has come to a standstill, e.g., at a station near the railroad grade crossing, and it then moves slowly toward the railroad grade crossing. At the minimum distance which has been established by the reference voltage, the railroad grade-crossing barrier, or warning device, will be operated whereas the predicted-time-of-arrival circuits would not satisfactorily operate the barrier.

In addition to the circuits shown for the two computers, at each barrier or grade crossing there are also provided, respectively, two high-gain summing amplifiers 142A, 142B. These have three inputs applied thereto, which are added. Two of these inputs are identical with those applied to the high-gain summing amplifiers 112A and 112B and the computer. These are the signals representative of the distance of the train from the crossing and the signal representative of the product of the gain factor times the velocity. The third input to each one of the high-gain summing amplifiers has been designated as the distant-crossing reference voltage derived from the sources, respectively 144A, 144B. These voltages are respectively proportional to the distance along section D2 to the distance along section D1, which must be added to the computed distance to secure a warning in time at the crossing X₁. Therefore, a train which is in the block section D1 and which is being tracked by the computer C₁₁, when the sum of the three signals applied to the high-gain summing amplifier 142A attains a sufficient amplitude, will operate the relay amplifier 146A, which will operate relay 148A. Contacts 148AC of this relay will be closed as the result. Closing of the contacts 148AC enables the energization of a warning relay 150 which is positioned at the next crossing X₂. The contacts 150C associated with this relay are connected in a circuit to energize the grade-crossing warning device, or barrier. It should be noted that these contacts are connected and parallel with the contacts 124C, which are associated with the time-of-arrival-prediction computer relay contacts.

The high-gain summing amplifier 142C has applied thereto a distant-crossing reference voltage from a source 144C, representing the distance D3 between the track section between barriers X₂ to provide the required operating voltage, the relay amplifier 146C will operate relay 148C, thereby closing contacts 148CC. These, as shown in FIGURE 5A, are connected to the relay 150. The contacts 150C of relay 150 can operate the warning device which is located at the barrier crossing X₃.

Computers C₃₄, C₂₃, and C₁₂ are operated when a train proceeds in the direction opposite to the one just considered. The mode of operation is identical with that described and therefore will not be gone into in detail. For example, for a train proceeding in the direction from the barrier X₃ to the barrier X₂, the computer C₂₃ would be tracking the train. Besides the relay amplifier 122B being operated when the predicted time of arrival coincides with that which has been inserted in the computer, the high-gain summing amplifier 142D can operate the relay amplifier 146D when the sum of the voltages representing the distance of the train from the barrier X₂ and the length of the track section D2 exceeds the value required to operate the relay amplifier 146D. Then the relay 148D is operated, in response to which its contacts 148DC are closed. This enables the energization of a relay 152, which thereby closes its contacts 152C. These contacts are connected in parallel with the contacts 124C and therefore operate the warning device at the X₁ barrier.

Of course, where the track distances between crossings

are sufficiently long, then the distance-crossing reference source and additional high-gain summing amplifier and relays need not be used.

The preceding analysis and discussion have assumed a rail condition such that the rails form a complete, homogeneous and uninterrupted circuit. However, one of the most annoying features from the safety standpoint, and one over which there is little control, is the problem introduced by a badly bonded rail. Although all bonding may be good initially, there is always the possibility that the bond resistance may increase with time, either from corrosion or from mechanical loosening. If such a high-resistance bond should come into existence, the total input impedance would rise and there would be an apparent increase in the distance from the crossing to the train.

If there is a high ballast resistance, the input impedance takes the form of

$$Z_{in} = RL + jwlL \quad (24)$$

where

R = the effective A.C. resistance of the track per unit of length

L = the length of track

l = the effective A.C. inductance per unit of length

$W = 2\pi$ times the excitation frequency

In other words, a linear relationship exists between Z_{in} and L , between the total resistive component and L , and between the total reactive component and L . However, the presence of a high-resistance bond introduces a further factor, the bond resistance R_j , into the equation. This factor is independent of L , and thus a linear relationship no longer exists between Z_{in} and L , the degree of nonlinearity being a function of the magnitude of R_j , the value of which can be rather large as in the case of a broken bond wire without de-energizing a track relay to stop a train with a block signal.

The reactive portion of the input impedance is caused largely by the fact that the transmission line is made from a conductor of high permeability, and is unaffected by the bad bond. The linear relationship between X_e , the total reactive component, and L is thus still in existence. Hence, if the resistance component of the computer input signal is ignored and only the reactive component observed, the influence of a bad bond can be eliminated. A circuit for accomplishing this result is shown in FIGURES 6 and 7. This circuit is shown as a modification of the embodiment of FIGURE 3. It should be obvious to those skilled in the art, however, that similar modifications could be made to the embodiments of FIGURES 1 and 2.

Turning now to FIGURE 6, a train 10 is shown moving from left to right on tracks 12A and 12B. An excitation oscillator 170 drives a power amplifier 172. As was the case in the other embodiments, this oscillator may provide an output having a frequency on the order of 50 cycles per second. The output of this amplifier is applied to the rails 12A, 12B; to point P directly and to point P' through a resistor 174. As before, the amplifier 172 and resistor 174 comprise a constant current generator. These points are also connected to a bandpass amplifier 176 whose frequency response is centered at the oscillator frequency and whose output is applied to a quadrature detector 178 which also has a reference input applied from the oscillator 170 through a phase shift network 179. In this modified circuit although a frequency of 50 cycles per second may be employed, a higher excitation frequency is preferably used, for example, a frequency of 265 cycles per second and the bandpass amplifier 176 is provided with a wider band width so that it will have greater phase stability and enable the phase characteristics of the circuits ahead of the quadrature detector 178 to remain constant with time.

The output of the quadrature detector 178 is applied to an inverting differentiator circuit 180 and also to a

summing amplifier 182. The output of the inverting differentiator circuit is applied to an amplifier 184, the output of which is connected to a second input of the summing amplifier 182. The summing amplifier output is connected to a high-gain amplifier 186. The output of the high-gain amplifier is applied to an amplitude comparator 188 wherein it is compared with a signal from a reference voltage source 190. The output of amplitude comparator 188 is connected to a relay amplifier 192 which operates the warning signal relay 194 when the signal applied thereto has a sufficient amplitude.

An override circuit is also provided, and this includes an amplitude discriminator 198 which receives the output from the quadrature detector 178 and compares it to the output of a reference voltage source 198. The output of amplitude discriminator 196 is connected to a relay amplifier 200 which drives a minimum distance override relay 202.

As was the case with the circuit of FIGURE 3, the input to differentiator circuit 180 and summing amplifier 182 is a voltage proportional to the distance L between the train and the excitation points P and P'. When differentiated, this voltage gives a voltage proportional to train speed. These voltages are utilized in the same manner as in FIGURE 3, the only difference being that the voltages depend only upon the reactive component of track impedance and not the resistive component. This will be apparent upon reference to FIGURE 7 which shows the quadrature detector 178 in greater detail, and to FIGURE 8 which shows various waveforms present in the system.

In FIGURE 7 it can be seen that the reference input from the oscillator 170 is applied through the phase shift network 179 to the input of a zero crossing detector 206. This zero crossing detector may, for example, comprise a Schmitt trigger circuit 208 followed by a differentiator 210 and produces a trigger pulse for a pulse generator such as a mono-stable or one-shot multivibrator 212 when the reference voltage goes through zero with a positive slope. The output of the multivibrator 212 is a pulse of very short duration which is amplified by pulse amplifier 214 and then applied to the gating input of a normally non-conductive gate 216. The signal input to the gate 216 is connected to the output of the bandpass amplifier 176.

When the gate 216 is turned on by the generation of a pulse from the multivibrator 212, it forms a low impedance charge or discharge path for a storage capacitor 218 in order that the capacitor may assume the instantaneous value of the A.C. signal input. This stored voltage in the capacitor 218 is corrected once each cycle of the carrier frequency and will thus follow modulation of the carrier frequency. An impedance matching amplifier 220 is coupled to the storage capacitor 218 and is provided with a high input impedance to minimize loading of the capacitor, substantial unity gain, and low output impedance to drive the differentiator 180, summing amplifier 182 and amplitude discriminator 196.

The action of this quadrature detector can best be understood by reference to FIGURE 8. As can be seen from this figure, the A.C. signal input to the track, waveform C, can be considered as two components added together: the resistive component, waveform, C_R , which is in phase with the A.C. reference voltage, waveform A; and the inductive component, waveform C_x , which lags the reference by 90 degrees. Since the resistive component C_R is always at zero when the gating pulse, waveform B, occurs, this component cannot contribute to the stored voltage on the capacitor which is thus representative only of the peak value of the inductive component of A.C. signal voltage.

The phase shift network 179 is used to set a slightly negative net phase angle between the A.C. signal and the A.C. reference inputs to the quadrature detector with a resistor substituted for the track impedance. This

assured that the phase angle will be zero or negative over the full tolerance of phase angles for all elements between the quadrature detector signal and the reference inputs. This is desirable as a positive phase angle would result in a greater apparent distance signal with a correspondingly shorter warning time. This phase shift network may be inserted into the signal path rather than the reference path, if desired.

The modified circuit of FIGURE 6 may, of course, be substituted for the embodiment of FIGURE 3 wherever the latter is used, for example, in the compounded circuit of FIGURES 4, 5A and 5B.

An additional benefit which may be obtained when this invention is used is that of being able to detect when a bad bond between rails, or broken, or open rail occurs. This can be readily detected when the voltage being monitored at the crossing increases beyond the value normally obtained when no train is in the track section. If this voltage increases beyond the normal value, then there is indicated an increase in input impedance which is most likely caused by a broken rail or bad bond. This feature is usable with any of the embodiments of the invention or even independently, if desired.

Apparatus for detecting such defective rails is shown in FIGURE 5A for the D1 and D2 track sections. It includes for respective track sections D1, D2 an amplitude discriminator 160A, 160B, respectively having one input connected to the output of the respective filters 108A, 108B, and a second input connected respectively to the output of bad-bond reference-voltage sources 162A, 162B. The latter establishes the normal open-track section voltage reference and the output of the filter 108A is the voltage actually existing across the track section. When the voltage actually existing across either the track section D1 or D2 exceeds the reference, then the associated one of the amplitude discriminators 160A, 160B applies an output to the relay amplifier 123 to cause it to actuate the grade-crossing warning system until the fault is corrected, thus overriding the computers. Alternatively, the output of either of the amplitude discriminators may be employed to transfer the grade-crossing control back to the conventional block system until the defective rail is repaired.

Various circuits have been represented herein by rectangles bearing the functional designation. These individual circuits are all well known in the electronic field, being amply described in the literature and for the most part commercially purchasable as individual components from several manufacturers, either using vacuum tubes or transistors. Accordingly, detailed descriptions of these circuits are omitted, since this would only add to the complexity of the description without adding any further understanding of the invention.

There has accordingly been described and shown herein a novel and useful railroad grade-crossing warning computer which actuates warning devices from information as to train speed and distance which is derived from the tracks.

We claim:

1. Apparatus for deriving from railroad tracks information for predicting the time required for arrival at a given location of a distant train which is moving on said tracks toward said location comprising means for applying an alternating-current signal with a constant-current level to said tracks at said location, means for deriving a first voltage at said location from said tracks which is representative of the distance of said train from said location, means for differentiating said first voltage to obtain a second voltage representative of the instantaneous speed of said train, and means for combining said first and second voltages to provide a third voltage which is a function of the time required for said train to arrive at said given location, and means for utilizing said third voltage for operating a warning device at said given location.

2. Apparatus for deriving from railroad tracks in-

formation for predicting the time required for arrival at a given location of a distant train which is moving on said tracks toward said location comprising means for applying an alternating-current signal with a constant-current level to said tracks, means for deriving a voltage at said location, rectifier means to which said voltage is applied for providing a first output voltage having an instantaneous amplitude representative of the distance of said train from said location and having the amplitude changing at a rate representative of the speed of said train, means for differentiating said first output voltage to obtain a second output voltage representative of said speed of said train, means for multiplying said second output voltage by a factor k to provide a third output voltage, and means to which said first and third output voltages are applied for obtaining a voltage representative of the difference of said first and third output voltages whereby said factor k represents the predicted time of arrival of said train at said given location when said difference voltage equals zero.

3. Apparatus as recited in claim 2 wherein there is included means to apply the output of said means for obtaining a voltage representative of the difference of said first and third output voltages to said multiplying means to establish the factor k .

4. Apparatus for deriving from railroad tracks information for predicting the time required for arrival at a given location of a distant train which is moving on said tracks toward said location comprising means for applying an alternating-current signal with a constant-current level to said tracks, means for deriving a voltage at said location, rectifier means to which said voltage is applied for providing a first output voltage having an instantaneous amplitude representative of the distance of said train from said location and having the amplitude changing at a rate representative of the speed of said train, means for differentiating said first output voltage to obtain a second output voltage representative of said speed of said train, means for subtracting two voltages to provide a resultant voltage, means connected to the output of said means for subtracting for amplifying said resultant voltage, means for multiplying the output of said amplifying means by said second output voltage, and means for applying said first output voltage and the output of said means for multiplying to said means for subtracting two voltages to establish the output of said amplifying means as the predicted time of train arrival.

5. Apparatus as recited in claim 4 wherein there is included means for establishing a reference voltage representative of the time interval desired before a train arrives at said given location for operating a warning device, means to which said reference voltage and output from said amplifier are applied for providing an output when these are equal, a warning device at said given location, and means for actuating said warning device responsive to said output.

6. Apparatus as recited in claim 5 wherein successive lengths of said track are bonded to each other and a defect in said bonding may occur known as an open bond, there being included in said apparatus a means for establishing an open bond reference voltage equal in amplitude to the output of said rectifier means when there is no train on said tracks, amplitude comparing means to which said open bond reference voltage and the voltage output of said rectifier means are applied for providing an output when said rectifier means voltage output exceeds said open bond reference voltage, and means for applying said amplitude comparing means output to said warning device to cause same to be actuated.

7. Apparatus for deriving from railroad tracks information for predicting the time required for arrival at a given location of a distant train which is moving on said tracks toward said location comprising means for applying an alternating-current signal with a constant-current level to said tracks, means for deriving a first

voltage at said location from said tracks which is representative of the distance of said train from said location, means to which said first voltage is applied for differentiating said first voltage to obtain a second voltage representative of the instantaneous speed of said train, a multiplying means having an output and a first and second input to which signals to be multiplied are applied, subtraction means to which the output of said multiplying means and said first signal are applied for obtaining a third signal representing the difference therebetween, and means for applying said third signal and said second signal to said respective first and second inputs of said multiplying means whereby said third signal represents the elapsed time at which said train will arrive at said given location measured from the instant said first voltage is derived.

8. Apparatus for deriving from railroad tracks information for predicting the time required for arrival at a given location of a distant train which is moving on said tracks toward said location comprising means for applying an alternating-current signal with a constant-current level to said tracks, means for deriving a first voltage at said location from said tracks which is representative of the distance of said train from said location, means to which said first voltage is applied for differentiating said first voltage to obtain a second voltage representative of the instantaneous speed of said train, means to which said second voltage is applied for differentiating said second voltage and providing a third voltage representative of the acceleration of said train, first, second, and third multiplying means each having two inputs to which voltages to be multiplied are applied and an output, means for applying said third voltage and said first multiplier output respectively to said second multiplier two inputs, inverter means to which said first voltage is applied for inverting said first voltage, means connected to said inverter means output for doubling the amplitude of said inverted first voltage, means to which the output of said third multiplier means is applied for doubling said third multiplier means output, summing means to which the outputs from said two means for doubling and said second multiplier means are applied for adding all said outputs and providing a fourth output voltage as the sum thereof, means for amplifying said fourth voltage, means for applying said second and amplified fourth voltages to the two inputs of said third multiplying means, and means for applying said amplified fourth voltage to the two inputs of said first multiplying means whereby said amplified fourth voltage represents the elapsed time required for said train to arrive at said location measured from the interval at which said first voltage is derived.

9. Apparatus for deriving from railroad tracks information for predicting the time required for arrival at a given location of a distant train which is moving on said tracks toward said location comprising means for applying an alternating-current signal with a constant-current level to said tracks, means for deriving a first voltage at said location from said tracks which is representative of the distance of said train from said location, means to which said first voltage is applied for differentiating said first voltage to obtain a second voltage representative of the instantaneous speed of said train, means to which said second voltage is applied for multiplying said second voltage by a factor whose value equals a desired time interval before said train arrives at said given location, means to which said first and multiplied second voltages are applied for subtracting said multiplied second voltages from said first voltage to provide a difference signal, means to which said difference signal is applied to detect when said difference signal is substantially zero at which time the time required for said train to arrive at said given location equals said multiplication factor.

10. In a track system consisting of different track sections in series wherein there is a grade crossing separa-

ting adjoining track sections, apparatus for providing a warning at a grade crossing of the expected arrival of a distant train which is moving on said tracks toward said grade crossing comprising means for applying an alternating-current signal with a constant-current level to each of said track sections, means for deriving at each crossing from a track section a first voltage representative of the distance of said train within that track section from said crossing, means for deriving from said first voltage a second voltage representative of the velocity of said train within that track section, means for multiplying said second voltage by a factor k to provide a resultant voltage, means for establishing a third voltage representative of the length of the track section succeeding that in which said train is moving, means for combining said first voltage and said resultant voltage, a first warning device for said grade crossing, means responsive to said combined first voltage and resultant voltage attaining a predetermined value for actuating said first warning device, 20 means for combining said first voltage, said resultant voltage, and said third voltage, a second warning device for the grade crossing between the succeeding two track sections, and means responsive to said combined first resultant and third voltages attaining a predetermined value 25 for actuating said second warning device.

11. In a track system as recited in claim 10 wherein successive lengths of said track are bonded to each other and a defect in said bonding may occur known as an open bond, there is included for each track section means for 30 deriving a voltage when no train is in said track section, means for establishing a bad-bond reference voltage having an amplitude substantially equal to that derived when no train is in said track section, amplitude comparing means to which both said voltages are applied for 35 providing an output whenever said voltage derived when no train is in said section exceeds said bad-bond reference voltage, and defective rail warning means to which said output is applied for actuating said defective rail warning means.

12. Apparatus for deriving from railroad tracks information for predicting the time required for arrival at a given location of a distant train which is moving on said tracks toward said location comprising means for applying an alternating-current signal with a constant level 40 to said tracks at said location, means for deriving a first voltage at said location from said tracks which is representative of the distance of said train from said location, said voltage having resistive and inductive components, means for modifying said first voltage by eliminating said resistive component from said first voltage, means for differentiating said modified first voltage to obtain a second voltage representative of the instantaneous speed of said train, and means for combining said modified voltage and said second voltage to provide a third voltage 45 which is a function of the time required for said train to arrive at said given location, and means for utilizing said third voltage for operating a warning device at said location.

13. Apparatus for deriving from railroad tracks information for predicting the time required for arrival at a given location of a distant train which is moving on said tracks toward said location comprising means coupled to said tracks for applying an alternating current signal with a constant level to said tracks at said location, 50 means coupled to said tracks for deriving a first voltage at said location from said tracks which is representative of the distance of said train from said location, said voltage having resistive and inductive components, means having a first input coupled to said deriving means and a second input coupled to a reference signal for modifying said first voltage by eliminating said resistive component from said first voltage, means coupled to said modifying means for differentiating said modified first voltage to obtain a second voltage representative of the instantaneous speed of said train, and means coupled to said

modifying means and said differentiating means for combining said modified first voltage and said second voltage to provide a third voltage which is a function of the time required for said train to arrive at said given location, and means coupled to said combining means for utilizing said third voltage for operating a warning device at said location.

14. Apparatus for deriving from railroad tracks information for predicting the time required for arrival at a given location of a distant train which is moving on said tracks toward said location comprising means for applying an alternating-current signal with a constant level to said tracks at said location, means for deriving a first voltage at said location from said tracks which is representative of the distance of said train from said location, said voltage having resistive and inductive components, means for modifying said first voltage by eliminating said resistive component therefrom, said means including gate means having a signal input coupled to said voltage deriving means for applying a gating signal to said gate means substantially only when the instantaneous value of said resistive component is zero, means for differentiating said modified first voltage to obtain a second voltage representative of the instantaneous speed of said train, and means for combining said modified voltage and said second voltage to provide a third voltage which is a function of the time required for said train to arrive at said given location, and means for utilizing said third voltage for operating a warning device at said location.

15. Apparatus for deriving from railroad tracks information for predicting the time required for arrival at a given location of a distant train which is moving on said tracks toward said location comprising means for applying an alternating-current signal with a constant level to said tracks at said location, means for deriving

5 a first voltage at said location from said tracks which is representative of the distance of said train from said location, said voltage having resistive and inductive components, means for modifying said first voltage by eliminating said resistive component therefrom, said means including gate means having a signal input coupled to said voltage deriving means, means coupled to said signal applying means for producing an output when said alternating-current signal crosses zero with positive slope, and means responsive to said output for applying a gating signal to said gate means only when the instantaneous value of said resistive component is zero, means for differentiating said modified first voltage to obtain a second voltage representative of the instantaneous speed of said train, and means for combining said modified voltage and said second voltage to provide a third voltage which is a function of the time required for said train to arrive at said given location, and means for utilizing said third voltage for operating a warning device at said location.

16. The apparatus of claim 15 wherein the output of said gate means is stored in storage means, said differentiating means being coupled to said storage means.

17. The apparatus of claim 15 wherein a small negative phase shift is introduced between said alternating-current signal and said derived voltage.
